UNITED STATES PATENT OFFICE.

FRED C. ALBER, OF CLEVELAND, OHIO.

COMBINED GAS AND ELECTRIC COOKSTOVE OR RANGE.

Application filed November 26, 1924. Serial No. 752,430.

My invention relates to an improvement in a combined gas and electric cook stove or range, my general object being to provide a cook stove or range in which separate sets 5 of electric and gas burners are particularly arranged and adapted to facilitate cooking operations.

In the accompanying drawings, Fig. 1 is a perspective view of a stove or range embodying my invention. Fig. 2 is a vertical section of the same stove showing the stepped arrangement of electric and gas burners therein. Fig. 3 is a top view of the electric burner attachment separate and 10 apart from the gas stove. Fig. 4 is a vertical section lengthwise of one end portion of the attachment, and Fig. 5 is a vertical cross section thereof on line 5—5 of Fig. 3. Fig. 15 6 is a sectional view horizontally of the upright member on line 6—6 of Fig. 5. Fig. 7 is a perspective view of another form of the invention adapted for attachment to one side 20 of the stove. Fig. 8 is a sectional view of the device shown in Fig. 7 as it appears attached to the stove. Fig. 9 is an electric wiring diagram for a pair of electric heaters 25 as used in my attachment.

In many communities where natural gas is available as fuel, the supply fails or frequently diminishes to a considerable extent in extremely cold weather, thus interfering with cooking operations where only gas is available in the range. Nearly all such communities have a source of electric current supply for illuminating purposes, but this supply is not conveniently available for electric cooking ranges or stove having the general utility of a gas range, inasmuch as local 35 ordinances or insurance requirements compel other apparatus to be installed and special house wiring to be made before such electric ranges can be connected and used. Exception is usually made for certain electric burners of predetermined wattage, and 40 I have therefore devised an attachment for a gas stove embodying such permissible electric burners, to permit cooking with either or both gas and electric burners, and have mounted the electric burners in offset relation 45 to the gas burners to permit both gas and electric cooking operations to be carried on simultaneously if desired. The electric burners are also mounted in a way to permit ready attachment thereof to a gas 50 range of a common type, and to be easily connected to the source of electric current,

and electric switches are provided for the electric burners and form a unitary part of the attachment, being mounted in a definite place thereon to facilitate assembly of the 60 parts and to permit the operator of the stove to manipulate such switches with safety while the gas burners are in operation.

Thus, the gas stove shown in the drawings, 65 comprises a frame 2 supported on legs 3 and carrying an oven 4 at one side of a grille or open top 5. A number of valved gas burners 6 are supported beneath top 5 in any conventional way, and top 5 lies in a horizontal 70 plane at a convenient working distance from the floor. To this well known type of gas stove, I attach a supplemental member comprising a horizontal shelf 7 having one or more electric burners 8 mounted therein, 75 the shelf being raised to the same plane as the top of oven 4 and also retired in respect to the front of the stove and the gas burners 6 beneath the front part of grille 5. A rigid side piece or panel 8' depends from one end 80 of shelf 7 and provides an upright support therefor when the shelf and this piece are bolted to the rear wall 9 of the stove and to the flat border of top 5. To facilitate bolting of the attachment to the stove shelf 7 has 85 a rear depending flange 10, and side member 8' is formed with lateral flanges 11, including a flange 12 at its top for shelf 7 which consists of a flat plate having circular flanged openings 14 formed therein. Electric heaters, 90 comprising channeled disks 15 are removably mounted within openings 14, a number of angular projections 16 being welded to the bottom of the plate to support such disks. The disks may be made of 95 vitreous insulating material and as shown have spiral channels therein containing a coil of helical resistance wire 17. In practice this coil may be tapped at several places to permit one or more sections thereof to be 100 placed in the electric circuit, using a suitable electric switch S for that purpose. Any 105 suitable electric heater or burner may be employed, and each heater controlled by a separate switch, and in the present case the manipulator of the switch is not exposed to the flames rising from the gas burners in stove top 5 because I mount such switches upon the upright panel 8' at one side of the stove or off-side in respect to said gas burners. However, shelf 7 is exposed in some degree to the heat rising from the gas burn- 110

ers, and therefore the electrical conductors and electric heating units are protected, and also concealed by means of a dished bottom plate 18 adapted to form an air chamber 19 beneath shelf 7. Bottom plate 18 is also utilized to lock the electric burners or disks 15 in place within the openings in the shelf. Thus, the shelf has an inwardly curled or beaded front edge 20 adapted to receive the front lip 21 of bottom plate 18, and each disk 15 has a central opening adapted to receive a stove bolt 22 which passes through a spacing bushing 23, and also a bolt opening in bottom plate 18 to permit a nut 24 to engage the bolt, thereby fastening the several parts detachably together. The electrical conductors for the heaters are covered with asbestos insulation and these conductors extend lengthwise through the chamber 19 and connect with the electric switches which are mounted upon the vertical side panel over openings 25 therein. These openings communicate with the outer end of said chamber to permit the electrical conductors to be readily connected to the switches, see Figs. 4 and 5, and the lead-in wires 26 for the switches pass through an insulating plug 27 which is also mounted in side panel 8' opposite chamber 19. Accordingly, the shelf and panel and the burners carried thereby provide a complete operative unit adapted to be readily attached to gas stoves of customary construction, and the electric shelf may be incorporated in a new stove when constructed or it may be made and sold as a separate article for attachment to gas stoves on the market and used either for cooking or warming purposes apart from or together with the gas burners.

I also show in Fig. 1 a side attachment for the stove, comprising a plate 30 having openings within which a second set of electric heating elements 15' are seated. These elements are constructed and secured in place in substantially the same manner as the electric heaters previously described, but the mode of attachment of the plate to the stove differs somewhat from that of shelf 7. Thus, plate 30 is provided with four legs 31. A pair of switches S' for controlling these electric heaters is mounted on the legs at the outer side of plate 30, and the legs on the opposite side are adapted to be inserted into slots or openings 32 in the border flange 33 of the stove top 5. The lower ends of the legs are bent laterally to permit them to engage the side wall 33 of the stove when the legs are inserted through openings 32, thereby supporting plate 30 in a firm and stable horizontal position flush with the top 60 of the stove. The attachment 30 is also thereby readily detached from the stove so that it may be carried away and used in other places. Thus, when plate 30 and heaters therein are detached it will be supported by the legs 31 in a level and elevated position above any suitable surface or base upon which they may rest.

What I claim is:

1. A cook shelf for a stove or range having a cooking top, containing a gas burner, said shelf being mounted upon a rear wall of said range and having electric heaters therein, and an electric switch for said heaters mounted at one end of said shelf and offside of said cooking top.
2. A cook shelf for a stove or range, having a cooking top, containing a gas burner, said shelf having a side panel mounted at the rear wall of said top, an electric heater mounted within said shelf, and a controlling switch for said heater mounted upon said side panel offside of said cooking top.
3. A cook shelf for a stove or range, having a cooking top, said shelf comprising a chambered top, portion having an electrical heater mounted therein, a downwardly extending side panel having a controlling switch for said heater mounted thereon and means for detachably securing said shelf to a range.
4. A cooking unit, comprising a horizontal top portion having an electrical heater mounted thereon, a downwardly extending side panel having a controlling switch for said heater and means for detachably connecting said working unit to a range, having a cooking top, said controlling switch being freely and accessible without danger when the cooking top of said range is used for cooking purposes.

In testimony whereof I affix my signature.

FRED C. ALBER.
